DRYER FOR THE HANDS OR SIMILAR ARTICLE

Irving Levine, ½ Triangle Electric Co.,
1513 Fairmount Ave., Ventnor, N.J.

Filed May 22, 1962, Ser. No. 70,239

Term of patent 14 years

(Cl. D4—3)

FIG. 1

FIGURE 1 is a view in perspective of a dryer for the hands or similar article, embodying my design and as seen from one side thereof; and

FIG. 2 is a side elevational view thereof as seen from the other side thereof.

The rear, not shown, is substantially plain and flat.

I claim:

The ornamental design for a dryer for the hands or similar article, as shown and described.
